ABSTRACT: Two soleholders are pivoted on vertical axes to a common carrier and laterally engage the toe portion of the skiing boot above the sole. The soleholders are normally locked against a pivotal movement. The carrier is mounted for pivotal movement against spring force on a toe iron part that is fixed to the ski. The carrier has for each soleholder a deflection-preventing means, which can be automatically disabled after a predetermined movement of the carrying member from its central position into the corresponding direction.

TOE IRON FOR SAFETY SKI BINDINGS

The present invention relates to toe irons for safety ski bindings, which toe irons comprise two soleholders, which are pivoted on vertical axes to a common carrier and laterally engage the toe portion of the skiing boot above the sole and are normally locked against a pivotal movement therefore. The carrier is mounted for pivotal movement against spring force about a vertical pivot pin on a toe iron part that is fixed to the ski.

Compared to the toe irons which have a ball detent and in which a pivoted soleholder carrier is locked relatively to a part that is fixed to the ski, such known toe irons have the advantage that they do not present a rigid resistance to forces which act obliquely or transversely to the longitudinal direction of the ski, but resiliently take up the forces. On the other hand, they have disadvantages which are undesirable in a safety toe iron intended for modern skiing. The main disadvantage resides in that they do not positively and suddenly release the toe portion of the skiing boot at the end of a sufficiently large elastic zone. In various types of toe irons, the skiing boot must actually squeeze out of the toe iron and past the soleholder. As a result, the friction is high and the force required for a release cannot be controlled or exactly adjusted. There is always a risk of the skiing boot being blocked in the toe iron; in this case the skiing boot is not returned to its normal position unless it is released so that a fall is inevitable.

For this reason it is an object of the present invention to provide a remedy in this respect and to improve and design a toe iron of the kind first described so that the disadvantages of the known toe irons are avoided in a simple and reliable manner, more particularly, that the toe iron has an exactly defined release position on both sides.

This object is accomplished in a toe iron for safety ski bindings, which toe iron comprises two soleholders, which are pivoted on vertical axes to a common carrier and laterally engage the toe portion of the skiing boot above the sole and are normally locked against a pivotal movement whereas the carrier is mounted for pivotal movement against spring force on a toe iron part that is fixed to the ski. In the invention the carrier has for each soleholder a deflection-preventing means, which can be automatically disabled after a predetermined movement of the carrying member from its central position into the corresponding direction. When the deflection-preventing means has been disabled, the soleholder can continue its pivotal movement alone and in doing so need not overcome the progressively increasing force of the damping spring acting on the carrier, but only the force of an optional weak restoring spring. The carrier is relieved and under the influence of the damping spring is returned to its normal position at the time when the means which prevent a deflection of the soleholder are disabled.

For this reason it has been found desirable to provide a design in which the points where the means for preventing a deflection of the soleholders are disabled coincide with the end points of the range of the pivotal movement of the carrier.

In order to ensure a satisfactory function of the toe iron in a sufficiently large elastic range, the soleholders must not extend rearwardly beyond a certain extent, toward the rear end of the ski, so that they cannot provide for the toe portion of the skiing boot the lateral control which is required for cross-country skiing.

In a development of the invention, the soleholders may be longer because the two means for preventing a deflection of the soleholders are connected to the carrier by a common pivoted plate. The pivoted plate is preferably pivoted to the free end of the carrier by means of a vertical pivot pin and extends toward the pivot pin which mounts the carrier. As a result, the pivotal axis of the pivoted plate is as close as possible to the toe portion of the skiing boot so that the blocking of the skiing boot during movements that are transverse to the longitudinal direction of the ski is virtually avoided with safety even where long soleholders are used which enable cross-country skiing.

5 Each means for preventing a deflection of a soleholder comprises suitably a locking pin, a locking lever, which is mounted on the soleholder for a pivotal movement against spring force, and a stop which is fixed to the ski and engageable by the locking lever. It has been found that the locking levers of both means for preventing a deflection of the soleholders are desirably under the action of a single spring element.

Further details of the invention will become apparent from the subsequent detailed description of various embodiments 10 of toe irons with reference to the accompanying drawings, in which:

FIG. 1 is a central longitudinal sectional view showing a toe iron according to a first embodiment,

FIG. 2 is a horizontal sectional view taken on line II-II 15 through the toe iron of FIG. 1,

FIGS. 3 and 4 show respective halves of the toe iron in different phases of the release movement in the same view as in FIG. 2,

FIG. 5 is a central longitudinal sectional view taken through 20 a toe iron according to a second embodiment,

FIG. 6 is a horizontal sectional view taken on line VI-VI 25 through the toe iron of FIG. 5, and

FIG. 7 is a top plan view showing a third embodiment of a toe iron with the top cover cut away for a better representation of the parts which are essential for the invention.

FIGS. 1 to 4 show a toe iron for safety ski bindings. This toe iron comprises a baseplate 1, which is secured by screws 2 to a ski 3 and carries a vertical pivot pin 4, on which a carrier 5 is pivotally mounted. A disc 6 is screw-connected to the pivot pin to hold the carrier against axial displacement. The carrier is pivotally movable from its normal position toward both sides against the force of a helical compression spring 7, which is prestressed as required. This pivotal movement is limited by two stop pins 8, 9, which are provided on the baseplate 1 and extend into slots 10, 11 of the carrier.

Soleholders 14, 15 are pivoted to the carrier 5 about vertical axes 12, 13. Each soleholder has a holding part proper consisting of a wing 16 or 17. These wings laterally engage the toe portion of the skiing boot above the sole. For adaptation to boots having different widths, the wings are adjustably secured to the soleholders 14, 15 by means which are not described in detail because they are known.

According to the present invention, a locking lever 20 or 21 is pivoted to each soleholder 14 or 15 on a vertical axis 18 or 19. The locking nose of each locking lever embraces a locking pin 22 or 23, which is provided on the carrier 5. The locking levers are two armed. Those arms which have no locking nose are under the action of a helical tension spring 24, which attempts to hold the locking levers in their locking position. The arrangement of the locking levers is such that their nose directly engages the corresponding stop pin 8 or 9 immediately before the limiting position is reached so that the locking lever is pivotally moved against the relatively small force of the spring 24 and the locking lever is thus disengaged from the respective locking pin 22 or 23 so that the respective soleholder 14 or 15, which is normally locked against a pivotal movement relative to the carrying member 5, can perform such outward pivotal movement against the force of the spring 24.

60 The prestressed helical compression spring 7 bears at both ends on a lug of the baseplate 1 and on the carrier 5 so that the latter is normally held in its central position shown in FIG. 2. If 65 which is transverse to the longitudinal direction of the ski and exceeds the opposing force of the prestressed helical compression spring 7, said force causes a pivotal movement of the carrier in a downward direction in FIG. 2. When the force decreases, the helical compression spring 7 causes a return of the carrying member 5 to its central position. Owing to the 70 deflection-preventing means according to the invention, the soleholder 15 has not moved relative to the carrier 5 during the outward and return pivotal movements. If a large force, which endangers the leg of the skier, engages the wing 17 of 75 the carrier 15, the carrier 15 is initially swung downwardly

again, as is shown in FIG. 3. FIG. 3 shows the instantaneous state in which the locking lever 21 just contacts the stop pin 9. A small further pivotal movement of the carrier 5 effects a pivotal movement of the locking lever about the axis 19 against the force of the return spring 24 so that the nose of the locking lever is disengaged from the locking pin 23. Thereafter, the soleholder 15 can perform a virtually unhindered outward pivotal movement, which is opposed only by the force of the spring 24, whereas the carrier 5 returns to its normal position under the action of the spring 7. The outward pivotal movement of the soleholder 15 ensures the virtually sudden release of the skiing boot at the end of the damping range. When the skiing boot has been released, the soleholder is returned to its initial position under the force of the spring 24 and is locked at the same time relative to the carrier. FIG. 4 shows the toe iron at the time when the skiing boot is released because the carrier 5 has returned to its central position.

The force by which the skiing boot is urged against the toe iron does not exceed the force which is required for a reliable control of the ski. Besides, the release position is exactly defined on both sides.

FIGS. 5 and 6 show a toe iron which substantially corresponds to the design which has been described with reference to FIGS. 1 to 4. For this reason, the same reference characters are used for like parts. Contrary to the embodiment which has been described before, this embodiment enables an adjustment of the force required for a release. The baseplate carries also a pivot pin 4 and forms a part of a guiding member 30, which is secured to the ski 3. A carrier 31 is pivoted to the pivot pin 4 and is held by the disc 6 against axial displacement. The carrier has a forked portion extending toward the tip of the ski. The insides of the two fork prongs 32, 33 are parallel to each other and serve as spring abutments for a helical compression spring 34, which extends transversely to the longitudinal direction of the ski through a bore in a bearing bracket 35, which is displaceably mounted in the guiding member 30 in the longitudinal direction of the ski. It carries a nonrotatable bolt 36, which is threaded into a tapped bushing 37. The latter carries an actuating handle 38 and is rotatably and axially nondisplaceably mounted in a cover 39. The sidewalls of the guiding member 30 form also abutments for the helical compression spring 34. Each sidewall is provided with a horizontal slot 40 or 41, which receives one of the fork prongs 32 or 33 of the carrier. The distance between the sidewalls equals the distance between the fork prongs. A slot 42 which extends in the longitudinal direction of the ski is formed in the upper wall of the guiding member 30 and receives a pin 43, which is firmly connected to the bearing bracket 35 so that the position of the spring in the guiding member is apparent. A scale for indicating the adjusted force which is required for a release is provided on one side of the slot in known manner, not shown. In the position shown in the drawing, the smallest force is required for a release because the spring has the smallest possible distance from the pivot pin 4. This distance can be increased by an actuation of the handle 38 so as to increase the force required for a release.

The deflection-preventing means for the soleholders correspond to those which are described with reference to FIGS. 1 to 4. Because the toe iron corresponds also in function to the one which has been previously described, that description is not repeated.

The wings 16, 17 are mounted on the soleholders 14, 15 for adjustment in height so as to enable an adaptation to soles which differ in thickness. For an upward and downward adjustment of the wings it is sufficient to turn their retaining screws 44 or 45. The same adjustment is also possible in the embodiment described first.

FIG. 7 shows a third embodiment of the toe iron according to the invention. The same reference characters are again used for like parts. A baseplate 50 is secured to the ski 3 by screws 2. As in the embodiment described first, the baseplate carries a vertical pivot pin 4, on which a carrying member 51 is pivotally mounted, which at its free end carries a vertical

pivot pin 52, which extends upwardly. A pivoted plate 53 is freely rotatably mounted on the pivot pin 52.

The soleholders 14, 15 are carried on vertical pivots 12, 13 by the pivoted plate. As a holding part proper, the soleholder 14 comprises a wing 54 and the soleholder 15 a wing 55. These wings 54, 55 are longer than the wings 16, 17 of the previously described embodiments so that they provide for the required lateral control of the toe portion of the skiing boot also during cross-country skiing. The locking pins 22, 23 serve also to cooperate with the locking noses of the locking levers 20, 21. In the present case, these locking pins are provided on the pivoted plate 53 rather than on the carrier. The deflection-preventing means and with them the soleholders are also under the action of a tension spring 24. The pivotal movement of the carrier 51 is limited by two stop pins 8 and 9 carried by the baseplate. Just as in the embodiments previously described, these stop pins serve to release the means which prevent a deflection of the soleholders. The carrying member 51 is pivotally moved against a spring force, which just as in the other embodiments results in a decrease of the force and, when the deflection-preventing means have been released, a return movement of the carrier to its normal position. As has been previously stated, the pivoted plate 53 is freely rotatably mounted on the carrying member 51. On the other hand, the soleholders are returned by the force of the spring 24 when the skiing boot has been released; the soleholders are locked relative to the pivoted plate at the same time. Because the pivotal axis of the pivoted plate is as close as possible to the toe portion of the skiing boot, the skiing boot cannot be blocked during the movement which is transverse to the longitudinal direction of the ski. In all embodiments, the wings of the soleholders facilitate the stepping into the binding. The toe portion of the skiing boot is automatically centered in such a manner that the forward end of the sole finally engages the carrier in the first two embodiments and the pivoted plate in the latter embodiment.

What is claimed is:

1. A toe iron for safety ski bindings, comprising a carrier mounted for pivotal movement relative to a ski, spring means biasing said carrier during pivotal movement of same tending to restore said carrier to its central position, two soleholders pivotally mounted to said carrier on vertical axes to engage laterally the toe portion of a skiing boot above its sole, lock means normally locking said soleholders against pivotal movement, said lock means comprising a locking lever mounted on each soleholder and a locking pin mounted to the carrier; and means coacting with said lock means for unlocking said lock means automatically after a predetermined pivotal movement of the carrier from its central position against the force of said spring means.
2. A toe iron according to claim 1, wherein said means coacting with said lock means is located at the end points of the range of the pivotal movement of the carrier.
3. A toe iron according to claim 1, wherein said lock means has a locking lever pivotally mounted on each soleholder, and spring means biasing said levers, and said means coacting with said lock means includes a fixed stop engageable by said locking levers.
4. A toe iron according to claim 3, wherein said spring means biasing said locking levers consists of a single spring element.
5. A toe iron according to claim 1 wherein the torque which opposes the movement of the carrier is variable by a variation of the length of the lever and that means are provided for indicating the force required for a release.
6. A toe iron according to claim 5, wherein the carrier on the side of its pivotal axis remote from the soleholders has a forked extension with the inside surface of the two fork parts being parallel, said spring means being held against the inside surfaces of the two fork parts which serve as spring abutments, and means to displace the spring means along said inside surfaces toward and away from the pivotal axis of said carrier.

7. A toe iron according to claim 6, wherein said spring means is a helical compression spring and is carried in a bearing bracket, which is slidably mounted in a fixed member.

8. A toe iron according to claim 7, wherein said means to displace said spring means includes a threaded bolt non-rotatably connected to a bearing bracket which is threaded received in a tapped bushing connected in turn with an actuating handle, said tapped bushing being rotatably and axially nondisplaceably mounted in said fixed member.

9. A toe iron according to claim 6, further including a fixed member provided with horizontally slotted extensions, which underlies said forked extension of the carrier with the distance between the slotted extensions equal to the distance between the two fork parts and two fork parts received in the slots of said slotted extensions.

10. A toe iron for safety ski bindings, comprising a carrier mounted for pivotal movement relative to a ski, spring means

biasing said carrier during pivotal movement of same tending to restore said carrier to its central position, two soleholders pivotally mounted to said carrier on vertical axes to engage laterally the toe portion of a skiing boot above its sole, lock means normally locking said soleholders against pivotal movement, said lock means and said soleholders being mounted on a plate pivotally mounted to the carrier, means coacting with said lock means for unlocking said lock means automatically after a predetermined pivotal movement of the carrier from its central position against the force of said spring means.

11. A toe iron according to claim 10, wherein the carrier is an elongated body pivotally mounted at one end and the pivoted plate is pivoted to the other end of the carrier by means of a vertical pivot pin, said pivoted plate extending toward the pivotal axis which mounts the carrier.
